UNITED STATES PATENT OFFICE.

CHARLES DUMKE, OF PORTLAND, WISCONSIN.

HORSE MARSH-SHOE.

SPECIFICATION forming part of Letters Patent No. 338,166, dated March 16, 1886.

Application filed February 2, 1886. Serial No. 190,616. (No model.)

To all whom it may concern:

Be it known that I, CHARLES DUMKE, of Portland, in the county of Dodge and State of Wisconsin, have invented a new and useful Improvement in Horse Marsh-Shoes, of which the following is a specification, reference being had to the annexed drawings, forming a part thereof, in which—

Figure 1 is a perspective view. Fig. 2 is an inverted plan view.

Similar letters of reference indicate corresponding parts in both figures of the drawings.

The object of my invention is to provide for horses a shoe having an extended surface, to be worn in soft marshy places, to prevent the horse's feet from sinking into the ground.

My invention consists in a board provided at opposite edges thereof with bars having series of oblong holes, and in combination therewith of eyebolts provided with T-shaped heads, and a lever fastener with the eyebolts, for clamping the board to the horse's hoof. The board A, which is of the general form of the horse's foot, but larger, is provided on its upper surface, near opposite edges, with the bars B, having offset middle portions, a, in which are formed series of transverse oblong holes b. The offset bars B are secured to the board A by bolts c, which extend through the board and through slots d in the ends of the bars. In the upper surface of the board A are formed recesses for receiving the heel and toe calks of the horse's shoe, and in the oblong apertures b of the bars B are inserted the eyebolts C, having T-shaped heads, which, after insertion in the holes of the bars, are turned transversely across the holes, so as to retain them in their places in the bars. Links D D' are received in the eyebolts C, the link D' being longer than the link D, and provided with a hooked cam-lever, E, which engages the link D and carries it over the end of the link D', as shown in Fig. 1, the lever E when in a locked position being about parallel with

the front of the horse's hoof, and the extreme end of the lever E being turned up slightly to cause it to engage the earth or grass, should the horse's feet sink into the earth so far as to bring the extremity of the lever E into engagement therewith. The foot of the horse is placed upon the board A, with the heel and toe calks of the shoe inserted in the recesses of the board, when the link D' is laid over the top of the horse's foot, the link D is slipped over the free end of the lever E, when the lever E is turned down into the position shown in Fig. 1, firmly clamping the hoof of the horse to the board A.

By changing the position of the eyebolts C in the apertured bars B the shoe may be adapted to horses' feet of different sizes, and the slots d of the end of the bars permit of their adjustment upon the bolt c.

The under surface of the board A is provided with two metallic strips, f, which are secured thereto by the bolts c, which also clamp the bars B.

Having thus described my invention, what I claim as new, and desire to secure by Letters Patent, is—

1. The combination, with the board A, provided with recesses for receiving the heel and toe calks of the horse's shoe, of the offset apertured bars B, the eyebolts C, provided with T-shaped heads, the links D D', and the cam-lever E, substantially as herein shown and described.

2. The combination, with the board A, provided with recesses for receiving the heel and toe calks of the horse's shoe, of the offset apertured bars B, the metallic strips f, the bolts c, the eyebolts C, having T-shaped heads, the links D D', and the cam-lever E, substantially as herein shown and described.

CHARLES DUMKE.
